(57) **CLAIM**

The ornamental design for an assay plate with sample landing mark, as shown and described.

DESCRIPTION

FIG. 1 is a top perspective view of an assay plate with sample landing mark in accordance with the present invention;

FIG. 2 shows a bottom perspective view thereof;

FIG. 3 shows a top view thereof;

FIG. 4 shows a bottom view thereof;

FIG. 5 shows a front view thereof;

FIG. 6 shows a rear view thereof;

FIG. 7 shows a right side view thereof;

FIG. 8 shows a left side view thereof;

FIG. 9 shows a top perspective view of another embodiment of an assay plate with sample landing mark in accordance with the present invention;

FIG. 10 shows a bottom perspective view thereof;

FIG. 11 shows a top view thereof;

FIG. 12 shows a bottom view thereof;

FIG. 13 shows a front view thereof;

FIG. 14 shows a rear view thereof;

FIG. 15 shows a right side view thereof; and,

FIG. 16 shows a left side view thereof.
